UNITED STATES PATENT OFFICE

FREDERIC ALBERT WHITAKER, OF METUCHEN, NEW JERSEY, ASSIGNOR TO GENERAL CERAMICS COMPANY, OF NEW YORK, N. Y., A CORPORATION OF NEW JERSEY

DESIGN FOR A RADIATING ELEMENT FOR GAS HEATERS

Application filed November 27, 1931. Serial No. 41,868. Term of patent 14 years.

To all whom it may concern:

Be it known that I, FREDERIC A. WHITAKER, a citizen of the United States, residing at Metuchen, in the county of Middlesex and State of New Jersey, have invented a new, original, and ornamental Design for Radiating Elements for Gas Heaters, of which the following is a specification, reference being had to the accompanying drawings, forming part thereof.

In the drawings—

Figure 1 is a top plan view of a radiating element, showing my new design; Figure 2 is an end elevation thereof; and Figure 3 is a side elevation thereof.

I claim:

The ornamental design for a radiating element for gas heaters, as shown.

FREDERIC ALBERT WHITAKER.
